J. J. LOWE

METHOD AND MEANS FOR VISUALLY DETERMINING THE FIT OF FOOTWEAR

Filed Feb. 6, 1919

Inventor,

Jacob J. Lowe;

By A. B. Blyham,
Attorney.

UNITED STATES PATENT OFFICE.

JACOB J. LOWE, OF BOSTON, MASSACHUSETTS, ASSIGNOR, BY MESNE ASSIGNMENTS, TO THE ADRIAN CORPORATION, INC., OF MILWAUKEE, WISCONSIN, A CORPORATION OF WISCONSIN.

METHOD AND MEANS FOR VISUALLY DETERMINING THE FIT OF FOOTWEAR.

Application filed February 6, 1919. Serial No. 275,310.

One of the most difficult things in regard to the purchasing of ready-made boots and shoes is the task of obtaining a fit. The new shoes may feel all right for the first few minutes, but after wearing them for a few blocks a painful pressure assures the owner that he has again made a failure in his desire to get a neat looking but comfortable shoe. Even the measuring stick used by so many salesmen only partially aids the selection, whether employed for taking the width of the foot as well as the length; for the foot, when sustaining the weight of the body, is considerably wider than when free from pressure.

The object of this invention is the effecting of means whereby the salesman, the purchaser and even the purchaser's advisory friend can visually know exactly how well a shoe is fitting, both under pressure and otherwise. To this end I have so disposed X-ray apparatus as to enable the positions of the bones of the foot within the new shoe to be clearly seen and distinguished from the outline of the shoe, whereby any cramping or compression of the toes is instantly made apparent.

In carrying this invention out, I provide a platform elevated sufficiently to carry the X-ray apparatus beneath it, with viewing means positioned above it, so that the wearer of new shoes can stand with his feet in the path of the rays and clearly see their condition.

In the drawings forming part of this specification, Figure 1 is a perspective view of apparatus embodying the preferred form of my invention. Fig. 2 is a sectional side view of the same. Fig. 3 is a sectional detail view of a detail thereof. Fig. 4 is a sectional elevation of a modification of the invention. Fig. 5 is a sectional side view of another modification.

The reference numeral 1 designates the platform beneath which is contained the complete X-ray apparatus comprising the X-ray globe 2, a transformer 3 suitably connected therewith, and a rotary converter 4, in case the current supply is D. C. instead of A. C. About the X-ray globe 2 is arranged a lead glass shield 5 having a central opening 6 for the passage of the rays upward.

The platform 1 is supported upon enclosing sides 7, an end 9, and steps 10, the latter being of course for the easy mounting of the shoe-purchaser to the platform.

Attached to the section of the platform farther from the steps is the viewing chamber 11 inclined away from the steps, and preferably formed with three viewing openings, the central opening 12 being elevated so that a man of medium height can look down through it when stooping somewhat and standing upon the platform, and the other two openings 13 being located low enough to accommodate men standing on the floor beside the apparatus.

The lower end of the chamber-front 14 is cut away sufficiently to form an opening 15 for the reception of the feet of a person standing on the platform close against the front 14. Immediately above this opening 15 but inclined to lie near the toes as well as near the instep, is a fluorescent screen 16 having immediately above it a plate of lead glass 17 for the protection of the observer, the two plates being slid into place through a slot 19 in the side 20.

As shown in Fig. 2, the viewing chamber 11 is out of plumb, being tipped away from the direction of the steps 10. The object of this is two-fold: first, to have the screen 16 at a substantial right-angle to the longitudinal dimension of the chamber and thereby to avoid the inaccuracy incident to viewing the screen-picture obliquely, and at the same time to present the screen properly to the feet as above set forth. Second, is to cause a person to have to lean over forward while visually considering the fit of the shoes being tried on. Thus leaning forward, his weight comes upon the ball of his foot, but if the chamber were vertical, his stooping to look down into the opening 12 would cause the main weight of his body to be over or behind his heels and thereby relieve his toes of the pressure needed for determining the very conditions sought to be learned.

A couple of handles 21 may be positioned at the juncture of the shoulders 22 and the neck 23, as shown in Fig. 1.

Each opening 12, 13 is provided with padded shields 24 for shutting out outside light when looking into the chamber, and in case only one or two persons may be using the

apparatus together, the unused opening can be covered by a cloth thrown over it.

In Fig. 4 is illustrated a modification of the device, comprising an inclined mirror 5 25 and a horizontal viewing passage 26, whereby a person can look down the chamber 11 without bending very much, but inasmuch as this bending is a desirable attitude, as above described, the structure first 10 described is preferable.

The structure shown in Fig. 5 is another modification wherein the apparatus box is provided with an inclined surface 27 against which a person can place his feet while seated in a chair and view the fitting of the foot-wear; but as it does not allow of adequate pressure of the ball of the foot, it does not fully serve the purpose desired.

The manner of employing this apparatus 20 is as follows: The person intending to purchase new foot wear, puts the same on his feet, mounts the steps 10, and stands upon the platform 1 with his newly clad feet projecting through the opening 15. He 25 then leans over forward and applies his face to the shielded opening 12, viewing his feet as pictured on the screen 16; only the bones and the dim outlines of the shoes being visible. If he sees that the bones of 30 the ball of a foot are pressed too closely together, or his toes crowded over each other, he needs no further evidence of the tightness of a shoe, no matter what the lack of feeling.

At the same time, the salesman or an accompanying friend or both are viewing the feet through the openings 13, the salesman introducing a pointer 30 through a hole 31 provided therefor in one or both sides of the viewing chamber, and pointing out the 40 points of ill-fit which he notes. This pointer can, of course, be easily seen as it moves over the fluorescent picture of the shoes and feet on the screen.

With this apparatus in his shop, a shoe 45 merchant can positively assure his customers that they need never wear ill-fitting boots and shoes; that parents can visually assure themselves as to whether they are buying shoes for their boys and girls which will 50 not injure and deform the sensitive bones and joints.

It should be understood that, although I 55 have illustrated and described, in detail, a concrete embodiment of my invention, the drawings and description are merely illustrative and, not in any sense restrictive, of the invention, numerous changes and modifications being possible without departing from the scope of the invention, which is 60 more particularly defined in the following claims.

What I claim is:

1. In a device of the class described and 65 in combination, a support for a foot, a viewing chamber extending upwardly from

the support and having a portion cut away to form an opening for the reception of the foot on said support, a fluorescent screen in said chamber above said opening, and an X-ray device beneath said support. 70

2. In a device of the class described and in combination, a support for a foot, an X-ray device below said support, a viewing chamber above the support, a fluorescent screen in said viewing chamber and spaced above said support whereby a foot may be placed between the screen and the support, said chamber extending upwardly above said support and having an observation opening positioned so that an observer can view an image of his own foot placed beneath the fluorescent screen. 80

3. In a device of the class described and in combination, a support for a foot, an X-ray device below said support, a viewing chamber above the support, a fluorescent screen in said viewing chamber and spaced above said support whereby a foot may be placed between the screen and the support, said chamber extending upwardly above said support and having an observation opening positioned so that an observer can view an image of his own foot placed beneath the fluorescent screen, and having a second observation opening whereby two persons may simultaneously view the foot. 90

4. In a device of the class described and in combination, a horizontal support for feet adapted to support a person in standing position, an X-ray device beneath said support, a viewing chamber extending upwardly above said support, a fluorescent screen in said viewing chamber and spaced from said support whereby the feet of a person standing upon the support may be placed between said screen and the support, said chamber being inclined in relation to said support and having an observation opening positioned so that an observer standing upon said support with his feet beneath said screen can view an image of his own feet, the chamber being inclined relatively to said support at an angle adapted to force such an observer to lean forward to view his foot and thus place weight upon the balls of the feet. 110

5. In a device of the class described and in combination, a support for a foot, an X-ray device beneath said support, a viewing chamber extending upwardly above said support, a fluorescent screen in said viewing chamber and spaced from said support whereby a foot may be placed between said screen and the support, said chamber being inclined in relation to said support and having a plurality of observation openings, one of said openings being positioned so that an observer can view an image of his own foot placed beneath the fluorescent screen, and said chamber being inclined at an angle 125 130

adapted to force such an observer to lean forward and thus place weight upon the ball of the foot.

6. In a device of the class described, a platform, an X-ray device below said platform, a viewing chamber rising from said platform, a fluorescent screen located in said chamber spaced from the platform, the front of the viewing chamber between said screen and platform being cut away to permit the introduction of the fore parts of the feet of a person standing on the platform, the viewing chamber being formed with two observation openings, one of said openings being in position suitable for the person standing upon the platform and positioning the feet beneath the fluorescent screen.

7. In a device of the class described and in combination, a platform, an X-ray apparatus beneath the platform, a viewing chamber above said platform, and a fluorescent screen located within said chamber and spaced from the platform to permit the introduction between the screen and platform of the fore part of the feet of a person standing upon the platform, the viewing chamber being inclined with relation to said platform and being formed with a plurality of observation openings, one of said openings being positioned so that an observer standing upon the platform can view an image of his own feet placed upon said platform below the fluorescent screen, and the chamber being inclined at an angle adapted to force such an observer to lean forward to view his feet and thus place weight upon the balls of the feet.

8. In a device of the class described and in combination, a support for the feet, X-ray apparatus beneath said support, a viewing chamber rising from said support, a fluorescent screen with said chamber and spaced from the support whereby a foot may be inserted between said screen and support, said chamber having a plurality of observation openings, and a hole for a pointer for the purpose of calling attention to details of an image on the screen.

9. In a device of the class described and in combination, a support for the feet, X-ray apparatus beneath said support, a viewing chamber rising from said support, a fluorescent screen within said chamber and spaced from the support whereby a foot may be inserted between said screen and support, said chamber having a plurality of observation openings, one of said openings being in position whereby the same may be used by the person positioning the feet between the screen and the support, and a hole for a pointer for the purpose of calling attention to details of the image on the screen.

10. In a device of the class described and in combination, a platform, an X-ray apparatus below said platform, a viewing

chamber rising from said platform and inclined with relation thereto, a fluorescent screen located within the chamber spaced from the platform and inclined with relation to said platform, said viewing chamber being cut away below said screen to afford an entrance for the fore part of the feet between the screen and the platform, the viewing chamber being formed adjacent its top with a plurality of observation openings affording a line of vision at an approximately right angle to said screen and one of said openings being in position for use by the person standing upon the platform and positioning the feet below the screen, the inclination of said chamber compelling such person to lean forward and thus throw weight upon the balls of the feet.

11. The combination as specified in claim 10 said viewing chamber having a hole therein for a pointer for the purpose of calling attention to details of the image on the screen.

12. A device of the class described comprising a box having a flat top, X-ray apparatus in said box, a viewing chamber rising from and inclined with relation to said top, and a fluorescent screen located within said chamber spaced above said top, said chamber being cut away at its front between said screen and top, a neck extending from the top of the chamber having a shoulder on one side thereof, observation openings being provided through the upper end of said neck and through said shoulder.

13. The method of visually determining the fit of foot-wear which consists in placing a shoe upon a foot, positioning the foot and shoe between a source of X-rays and a fluorescent screen, placing weight upon the foot to produce a broadening of the foot, and viewing the image of shoe and foot on the fluorescent screen.

14. The method of visually determining the fit of foot-wear which consists in placing a shoe upon a foot, positioning the foot and shoe between a source of X-rays and a fluorescent screen, placing the weight of the body upon the ball of the foot to produce a broadening of the foot, and viewing the image of the shoe and foot upon the fluorescent screen.

15. In a device of the class described and in combination, a horizontal support for feet adapted to support a person in standing position, an X-ray device beneath said support, a viewing chamber extending upwardly above said support, a fluorescent screen in said viewing chamber and spaced from said support whereby the feet of a person standing upon the support may be placed between said screen and the support, said chamber having an observation opening positioned so that an observer standing upon said support can view an image of his

own feet placed beneath the fluorescent image of shoe and foot on the fluorescent screen.

16. The method of visually determining the fit of foot-wear which consists in placing a shoe upon a foot, positioning the foot and shoe between a source of X-rays and a fluorescent screen, and self-viewing the

image of shoe and foot on the fluorescent screen.

In testimony that I claim the foregoing ¹⁰ invention, I have hereunto set my hand this 4th day of February, 1919.

JACOB J. LOWE.
